UNITED STATES PATENT OFFICE.

ALBERT C. WENDELKEN, OF MARIETTA, OHIO.

SASH.

1,238,703.

Specification of Letters Patent. Patented Aug. 28, 1917.

Continuation in part of application, Serial No. 34,887, filed June 18, 1915. This application filed January 26, 1917. Serial No. 144,686.

To all whom it may concern:

Be it known that I, ALBERT C. WENDELKEN, a citizen of the United States, residing at Marietta, in the county of Washington and State of Ohio, have invented certain new and useful Improvements in Sashes, of which the following is a specification, reference being had therein to the accompanying drawing.

10 My invention relates to window construction and the present application is a continuation in part of my co-pending application Serial No. 34,887, filed June 18, 1915.

15 The invention herein seeks to provide a metallic shuttered window and slats therein being arranged in sash frames so that the sash may be raised and lowered like an ordinary window, the said slats themselves being arranged so that they may be opened and closed with great ease and convenience. In some instances it is also advantageous to cover the sash opening with a wire screen permanently attached to the sash frame.

20 The adaptability of a window is greatly increased thereby, since every desired variation in the admission of light and air and protection from the elements may be obtained. To my knowledge a device has not heretofore been made that will conveniently regulate these elements and my invention therefore constitutes a very important advance in the art.

25 By my construction of the sash hereinafter referred to as the all-weather sash, I am, among other advantages, able to adjust the slats to any desired angle and lock them.

My invention is illustrated in the accompanying drawings in which:—

30 Figure 1 is a perspective view of a window embodying my invention.

Fig. 2 is a vertical section through one of the sashes.

Fig. 3 is a fragmentary inside view of a sash.

45 Fig. 4 is a side elevation of Fig. 3 looking from the right.

Fig. 5 is a fragmentary horizontal section of a sash.

Fig. 6 is a detail of a slat.

50 Fig. 7 is a perspective view, on a larger scale of a slat detached.

Fig. 8 is a broken perspective view of the lift rail.

55 Fig. 9 is a broken perspective view of the side rail.

Fig. 10 is a broken perspective view of the top rail.

Fig. 11 is a broken perspective view of the bottom rail.

Fig. 12 is a detail view of a modified form 60 of frame of metal, upon which all metal parts may be assembled as a unit.

Fig. 13 is a vertical transverse section 65 through the hinged sill or cover for the sash pocket.

Fig. 14 is a section at right angles to and on the line $x-x$ of Fig. 13.

Referring more specifically to the drawings, the upper and lower all-weather sash frames 1 and 2 are of a form commonly 70 given to sash frames. These frames are of suitable size and shape to completely cover the window frame and each may be raised and lowered in the channels formed by the dividing stops. The sash frames may be 75 made of wood as indicated, or of metal.

The all-weather sash may be installed in conjunction with the ordinary glass sash or may be used to replace the glass sash ordinarily installed.

80 It will be noticed that when assembled as shown in Fig. 2, the slats are all pivoted at both ends near the upturned edge 3 to the side rail 8 and at the ends or corners near the downwardly turned edge 4, to an angle 85 bar hereinafter called the lift rail 7, which lift rail is connected with the operating bar 11 by a link member 12. There is one of these lift rails on each side of each opening, but as the different elements of this assem-

blage are rigid and when assembled as stated will work in parallel motion, it is necessary 90 only to connect with one of the lift rails, in order to open and close the slats, and so a single operating bar is mounted to one side 95 of the slat opening as shown in Figs. 2 and 3. This operating bar is mounted on the sash by means of a threaded stud carried by the bar projecting through a slot in the side rail 8 and held therein by means of a suitable thumb nut which takes onto the threads on the stud. A link member 12 is pivotally connected at its opposite ends, one end to the operating bar and the other end to the lift rail 7, as clearly shown in Figs. 2, 4 105 and 5, for the purpose of transmitting motion from the operating bar to the lift rail 7.

100 By the arrangement shown, various degrees of movement of the operating bar will produce corresponding degrees of adjust- 110

ment of the slats, and consequently the slats may be locked in any degree of adjustment by turning the thumb nut so as to thread it along the screw toward the operating bar 5 and bind it against the intervening surface of the sash. The same result may be obtained by other slight variations from this arrangement without departing from the idea involved.

10 The top rail 9 and the bottom rail 10 are fixed respectively to the inner face of the top and bottom of the openings of slat sash frames 1 or 2. The top rail, or the fixed slat 9 at the top of the opening extends inwardly, then is turned downwardly and then inwardly, where it will engage with the nearest adjustable slat as clearly shown. The bottom rail, or fixed slat 10 at base of opening, extends upwardly, then inwardly 15 across the bottom rail of sash, then upwardly, then outwardly where it will engage with the adjustable slat next above as clearly shown in Fig. 2. Thus the extreme outer extension of the slat just referred to forms a facing for the lower member or bottom rail of the sash frame. Both slats 9 and 10 are secured by nails, screws or by any other suitable means.

20 Metallic side rails 8 are secured to the sides of the sash frames, overlapping the fixed top and bottom slats 9 and 10 at their outer ends, and having the section shown in Figs. 5 and 9. As clearly indicated in Fig. 5, these side strips are projected an appreciable distance from the face of the sash frame to which they are secured to overlap the slats, then turned back upon themselves to within a short distance of the inner edge 25 of the frame and outwardly at substantially right angles.

20 The adjustable slats are pivoted at their inner edges to the out-turned portions of the side rail 8. Both ends of each slat are turned outwardly at substantially right angles as clearly indicated in Fig. 7, and a pivot lies in each case at the inner end of the out-turned portion. The pivot consists of eyelets of any approved construction, though any equivalent means such as rivets 45 may be used if desired. In the very light but strong construction of this embodiment, I find small brass or iron eyelets exceptionally efficient for this purpose. One edge of each slat is turned in one direction and the other in the opposite direction as 3 and 4 at an angle to the main body 6. Specifically, when the slats are closed as in Fig. 2, the upper edge of the slat is turned outwardly, and the lower edge inwardly. The lift rail 50 7 in this case is a mere strip of sheet metal of angular shape having its outer edge turned toward the side of the sash frame as shown in Fig. 5 and closely adjacent thereto, whereby there is a closed space between the lift rail 7 and the side rail 8, there being

provided a lift rail at each end of the slat. The slats are pivoted thereto at the lower or outer ends of the out-turned end portions by means of eyelets or rivets as in the case of their connection to the side rail.

70 A means is provided by which the slats may be operated from the inside. This consists of an operating bar or rod 11 which extends longitudinally of the space between the lift rail 7 and the side rail 8 on one side, a stud on the upper end of which projects through the slot in side rail 8 and is attached to the lift rail by means of a link member 12.

75 The threaded stud 13 at the upper end of the operating bar 11 which projects through the aperture, is suitably capped by a thumb nut 14, by means of which the slats are operated and secured at the angle desired.

80 The all-weather sash completely covers the entire opening and hence the entire window space may be thrown open for the purpose of ventilating by simply opening the slats. To open the slats, one has only to grasp the thumb nut of the operating bar 11 and raise it, whereupon the lower ends of the slats are simultaneously raised to the position shown in Fig. 4 by means of the operating bar, the link member and the lift rail. The thumb nuts, by being turned, 90 retain the slats in any adjusted position. By the foregoing, it will be seen that any portion of the entire window area may be used for purposes of ventilation; or for lighting, without unfavorably affecting the 95 conditions of ventilation. The slats may be so adjusted as to admit only the desired degree of light. When the operating bars 11 are pushed downwardly to the limit, the slats are tightly closed and gripped together, as shown clearly in Fig. 2. The 100 action of the link member, connected with the operating bar and lift rails transmits the closing pressure most effectively. When closed the inwardly turned edges of the slats overlap snugly the outwardly turned edges of the same, the inwardly and outwardly turned portions of the top and bottom rails coöoperating with corresponding 105 portions of the movable slats thus most effectively closing the opening. Rain or snow cannot penetrate the all-weather sash. The overlap of the inwardly turned edges of the slats upon the outwardly turned edges, the outwardly turned ends of the slats and 110 the relation of these with the top, bottom and side rails, are sufficient to prevent the beating in of wind driven snow or rain in very severe storms. The snug fit, the general outward trend of the overlap of the main 115 surface of the slats when they are closed, have much to do with this efficient service. The slats, owing to the peculiar angles turned thereon, which gives great rigidity thereto, may be made of light gage sheet 120

125 130 135

metal, thereby insuring an easy operation thereof, and yet possess more than sufficient strength to withstand abnormal wear to which they may be subjected.

- 5 By this novel construction of the slats and the arrangement whereby they may be locked in any position, any variation in the admission of light and air may be had from practically totality to zero. The slats may
 10 be thrown entirely open, allowing the air to come directly through, or they may be partially closed and locked in that position so that the air is directed upward as it comes through the slats. A fly screen 15 may be
 15 attached to the sash for obtaining the additional advantage of keeping the insects from entering and still having ventilation. (See Fig. 12.)

Owing to these features of adaptability, 20 the all-weather sash may be used as a ventilator or a shutter, or both. The great field for the use of a device of this sort is widely apparent, since the greatest necessity exists and a want has long been felt for a window 25 of a quickly transformable character. Sunlight and air are two necessities in winter and summer respectively and through the use of the all-weather sash as much of one or the other, or both, as may be desired, can 30 be obtained.

Not only in residences, for sleeping porches, sun parlors, etc., is my invention of advantage, but it has a special utility in portable houses, hotels, infirmaries, school buildings 35 and hospitals, where the problems of lighting and ventilation have ever been troublesome ones. The all-weather sash also offers the solution of ventilating problems in factories and office buildings, theaters, Pullman 40 cars and refrigerator cars.

In Figs. 13 and 14 I have shown a means for preventing water from entering the sash pocket, either by the driving of rain or snow from without, or by condensed or other 45 moisture running down the sash guides along the sides of the frame. As shown in Fig. 14, the side frame is transversely channeled out at 16, in a line following the contour of the top of the pocket cover. At 50 each end of the pocket cover a sliding auxiliary or extension cover 17 is provided, which I preferably make of sheet metal, such as copper or galvanized iron or zinc. Each of these extensions slides upon the pocket cover, 55 and is exactly adapted to the contour thereof, being formed with flat, sloping sections, 18, 19, 20, vertical off-sets 21 and 22, and a depending lip 23 on the outside face 60 of the pocket cover which extends down far enough to cover the edge thereof. The vertical off-sets 21 and 22 may be flush with the sash guides, but preferably are placed intermediate of the guides, in the sliding space, the bottom of the sash being rabbed to fit over the off-set, not only in the

extension, but in the entire length of the pocket cover. The purpose of this construction is to better exclude drafts of air and moisture than would be the case if the off-sets abutted on the inner face of the sash. 70 The extension members are slotted at 24 and 25, and each slot works on a screw or stud set into the wooden pocket cover. A suitable handle 26 is fastened to each extension, so that it may be readily slid back and forth. 75

In order to still further protect the sash pocket, I form a groove 27 in the lower face of the pocket cover and parallel with the edge thereof, which when the cover is closed, takes over a metal feather 28 secured to and 80 covering the upwardly projecting edge of the outer sill piece 29, which is a rigid and immovable part of the frame structure.

With this construction, when the sash are all in the pocket, the sash cover may be 85 closed and the extension slides pushed outwardly into their slots, whereupon the interior of the pocket will be completely 90 inclosed and protected against the entrance of any dust or moisture from without. When the sash are raised out of the pocket, the pocket cover may again be closed, the slides pushed home in their slots, and the sash closed, so as to form a complete weather 95 proof closure for both the sash pocket and the interior of the room or sleeping porch.

It will be observed that in Fig. 12 I have shown a complete metal unit consisting of frame, slats and screen assembled together and ready for attachment to the wooden or 100 other frame. As I believe this to be original with me, I shall claim the same broadly and specifically.

Having thus described my invention, what I claim and desire to secure by Letters 105 Patent is:

1. A sash structure comprising the following instrumentalities: a sash frame, metal side strips for said frame, metal cross strips at the top and bottom of said frame having 110 their edges bent over to form horizontal flanges at top and bottom of the frame opening, a plurality of metal slats each flanged at opposite ends, with its longitudinal edges turned in opposite directions, pivoted at one 115 edge of each of its opposite end flanges to one of the metal side strips of the frame, a metal connecting strip pivoted to the free edges of the flanges at each end of all of the slats, and common operating means 120 mounted on one side strip and adapted to effect parallel motion of all the slats together, the upper and lower edges of each intermediate slat engaging with and closing 125 against the lower and upper edges respectively of the adjacent slats when all the slats are closed and the upper and lower edges of the upper and lower slats at such time engaging with and closing against the flanges on the upper and lower cross metal strips at 130

the top and bottom of the frame respectively, whereby the entire area of the frame is tightly sealed when the slats are closed and said entire area is opened when the 5 slats are opened.

2. A window and wall structure comprising a frame and a plurality of sash arranged to slide therein in close proximity to each other to afford a substantially weather-tight 10 junction at overlapping parts, each sash having a screen attached to the inner face thereof and covering the entire opening therein, metal side strips mounted in the opening in the sash between the inner and 15 outer faces thereof, a plurality of metal slats extending across the opening in the sash between said side strips and pivoted at their inner edges in said side strips near the inner face of the sash, movable side strips 20 pivoted snugly to the outer corners of said slats to act as movable braces therefor, a sliding rod countersunk in the inner face of said sash, means for transmitting motion from said sliding rod to one of said movable strips to open and close the slats, and 25 means for locking said sliding rod in different positions.

3. A structure for sash to be slidably mounted in a window frame in compact arrangement, consisting of a sash frame or 30 sash having an opening therein, metal side strips mounted in the opening in the sash, a plurality of metal shutter slats pivoted at their inner corners in said side strips close 35 to the inner face of the sash, movable side strips pivotally connected with the slats near the outer corners, an adjusting rod slidably mounted in the inner face of the sash between one of said strips and the sash frame, 40 and means for transmitting motion from said adjusting rod to said movable side strip.

4. A sash structure comprising a sash frame, a screen secured across the inner face of the opening in the frame completely cov-

ering the opening, a plurality of shutter 45 slats pivoted at their inner edges in the opening of said sash frame near the inner edge of the opening, operating means for said slats mounted on the frame and extending inwardly from the inner face thereof 50 to be operated from the inner side of the sash, and motion transmitting means connecting said operating means with the outer edges of said slats, whereby said slats may be swung downwardly and inwardly toward 55 the screen to close the opening covered by the screen, and upwardly and outwardly away from the screen in opening.

5. A metal slat structure for sashes comprising metal side strips each bent to form 60 a facing strip extending along the inner face of one side of the opening of the sash and a perpendicularly projecting flange extending along the side of the opening near the inside edge, metal cross strips at top 65 and bottom of the sash opening substantially covering the top and bottom of said opening and having their edges bent over to form offset horizontal flanges, a plurality of slats each flanged at opposite ends 70 with its edges turned in opposite directions to form longitudinal flanges, all of said slats being pivoted at their inner corners to the flanges of said side strips, metal connecting 75 bars for said slats L-shaped in cross section with one flange of each pivoted to the outer corners of the slats and the other flange extending from the edges of the slats toward the adjacent side of the sash opening, operating means mounted in the facing strip 80 of one of said side strips, and means for transmitting motion from said operating means to one of said connecting bars.

In testimony whereof I affix my signature.
ALBERT C. WENDELKEN.
